US0D1015180S

(12) **United States Design Patent** (10) **Patent No.:** **US D1,015,180 S**
(45) **Date of Patent:** **** Feb. 20, 2024**

(54) **MOTION SENSOR**

(71) Applicant: **Amazon Technologies, Inc.**, Seattle, WA (US)

(72) Inventors: **James Siminoff**, Pacific Palisades, CA (US); **Mark D. Siminoff**, Mountain View, CA (US); **Wen-Yo Lu**, Pasadena, CA (US); **Christopher Loew**, Palo Alto, CA (US); **Jia Li**, Nutley, NJ (US); **Wei-Chung Wang**, New Taipei (TW); **Gregory Berlin**, Spring City, PA (US); **Eric S. Micko**, San Jose, CA (US); **Andrew Louis Russell**, Havertown, PA (US)

(73) Assignee: **AMAZON TECHNOLOGIES, INC.**, Seattle, WA (US)

(**) Term: **15 Years**

(21) Appl. No.: **29/865,991**

(22) Filed: **Aug. 23, 2022**

Related U.S. Application Data

(62) Division of application No. 29/723,865, filed on Feb. 11, 2020, now Pat. No. Des. 962,101.

(57) **CLAIM**

The ornamental design for a motion sensor, as shown and described.

DESCRIPTION

FIG. 1 is a top, front, right-side perspective view of a first embodiment of a motion sensor;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the motion sensor that form no part of the claimed design.

1 Claim, 8 Drawing Sheets
